UNITED STATES PATENT OFFICE.

CHARLES S. BIRD AND GEORGE R. WYMAN, OF WALPOLE, MASSACHUSETTS; SAID
WYMAN ASSIGNOR TO SAID BIRD.

TUBE-FORMING STRIP.

1,101,990.

Specification of Letters Patent. Patented June 30, 1914.

Application filed October 9, 1911. Serial No. 653,641.

To all whom it may concern:

Be it known that we, CHARLES S. BIRD and GEORGE R. WYMAN, both of Walpole, in the county of Norfolk and State of Massachusetts, have invented a new and Improved Tube-Forming Strip, of which the following is a specification, reference being had to the accompanying drawings, forming part thereof.

10 This invention has reference to improvements in strips from which electrical conduits and other tubular structures can be formed.

One object of the invention is to so construct a tube forming strip that no raw edges are present in the finished tube.

Another object of the invention is to so construct a tube forming strip having a layer of insulating fiber or material of comparatively coarse quality that such layer, in the strip as well as in the completed tube is protected from contact or exposure.

Another object of the invention is to so construct a tube forming strip that, when said strip is formed into a tube, the drawing into said tube of wires or other articles is facilitated.

Other objects of the invention will appear from the following description.

20 The invention consists in a tube forming strip of material having its edge portions turned inward whereby the edge of the strip is formed by a fold of the material as distinguished from a raw cut edge of such material.

The invention also consists in a tube forming strip comprising a filling strip and a layer of hard paper secured to said filling strip.

30 The invention also consists in a tube forming strip comprising a filling strip of comparatively coarse fibrous material and a wrapper of hard and comparatively fine paper secured to said filling strip and covering the edges thereof.

The invention also consists in a tube forming strip having ridges extending longitudinally or approximately longitudinally of the strip.

40 The invention also consists in such other novel features of construction and combination of parts as shall hereinafter be more fully described and pointed out in the claims.

50 Figure 1, represents a plan view of the

improved tube forming strip, in its preferred form, parts of the same being broken away to show the filling or insulating strip. Fig. 2, represents an enlarged sectional view of the strip as taken on line 2—2 Fig. 1, 60 Fig. 3, represents a cross sectional view of a tube formed from the improved strip as taken on line 3—3 Fig. 4. Fig. 4, represents a view of a tube or conduit formed by bringing the edges of the strip together approximately in a straight line. Fig. 5, represents a view of a tube or conduit formed by winding the improved strip spirally.

Similar numerals of reference designate corresponding parts throughout.

Strips of this nature are used to form the inner walls or surfaces of tubes and more particularly of tubes adapted to be used for insulating conduits for electric wires which wires are usually drawn into the tubes after the tubes are secured in building structures. Obviously it is important to so construct the tubes that the inner walls thereof shall not present raw edges which may retard the drawing in of the electric wires or cables by a tendency to engage the wrappings or insulating coverings of said wires or cables. It is also of some importance that, where a strip of insulating fiber is incorporated in the wall of the tube, the raw edges of said strip be so confined that they cannot swell out or spring toward the bore of the tube.

In carrying our invention into practice in its preferred form we take a strip 5 of coarse paper stock or of fibrous material constituting a core, and adapted, to some extent, to electrically insulate a wire or cable around which said strip is wrapped. This strip 5 is placed against one surface of the outer strip 6 of hard strong paper and is preferably secured thereto by adhesive, the edge portions of the strip 6 being wrapped over, and, preferably, secured to the back of the strip 5 whereby the edges, 7, 7 of the complete strip are slightly rounded. The combined strips 5 and 6 are now, or at some time during the process of manufacture passed through any suitable machine by which parallel creases are formed in the wrapper 6 approximately longitudinally of the strip whereby the ridges 8, 8 are formed by the material of wrapper 6 on that surface thereof which is intended ultimately to form the inner surface or lining of the completed tube or conduit. When the

strip is formed into a tube as shown in Figs. 4 and 5 for insertion into a pipe, the rounded longitudinal edges 7, 7, where they meet form a longitudinally extending groove 6 corresponding to those formed by the ridges 8, so that there is no break in the continuity of the longitudinally grooved or creased inner face of the insulating tube. The strip is reinforced and strengthened by transversely extending ribs or creases 9 on the outer face thereof which are produced simultaneously with the forming of the corrugated inner face, the formation of these ribs or creases leaving the inner face of the strip indented transversely at spaced intervals as shown at 10, Fig. 1, where the forming die or roll compresses the material so as to force the same outwardly on the outer face and produce the ribbed or creased outer face of the strip. We prefer that the strip 6 be of sufficient width to wrap completely around the strip 5 as by this construction the hard and closely condensed material of the strip or wrapper 6 to some extent protects the coarser fiber of strip 5 from moisture.

It is not our intention to limit our invention by the above statement of the kind of material preferably used nor as to the shape or extension of the ridges or projections 8, 8 and it is obvious that such ridges or projections may be omitted in some cases.

Having thus described our invention we claim as new and desire to secure by Letters Patent.

1. A strip adapted to form tubular insulation, comprising a core and a relatively thin covering therefor, the covering being adhesively secured to the core and having a cross-sectional length to provide overlapping ends, the inner face of the strip being creased to provide a plurality of corrugations in the covering substantially continuous in cross-section and extending lengthwise of the strip, the creases extending into the core.

2. A strip adapted to form tubular insulation, comprising a core and a relatively thin covering therefor, the covering being adhesively secured to the core and having a cross-sectional length to provide overlapping ends, the inner face of the strip being creased to provide a plurality of corrugations in the covering substantially continuous in cross-section and extending lengthwise of the strip, the creases extending into the core, said strip having lateral creasings spaced apart and of greater width on the outer face than on the inner face.
